UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

PULL SWITCH.

Application filed May 18, 1922. Serial No. 561,861.

To all whom it may concern:

Be it known that I, REUBEN B. BENJAMIN, a citizen of the United States, residing at Chicago, in the county of Cook and State of Illinois, have invented new and useful Improvements in Pull Switches, of which the following is a full, clear, concise, and exact description, reference being had to the accompanying drawing, forming a part of this specification.

My invention relates to pull switches.

One of the objects of my invention is to provide an improved pull switch mechanism in which provision is made for an angular adjustment between the switch mechanism and the tubular guide for the flexible pull member.

A further object of my invention is to provide an improved pull switch mechanism in which the switch mechanism may be angularly adjusted with respect to the means which secure it to its canopy or housing, so that the switch mechanism may be properly supported.

Further objects will appear from the detailed description to follow and from the appended claims.

In the drawings in which an embodiment of my invention is shown—

Figure 1 is a sectional view showing a pull switch mechanism mounted in a canopy;

Fig. 2 is a plan view of the switch mechanism;

Fig. 3 is a section on the line 3—3 of Fig. 2;

Fig. 4 is a bottom plan view of the switch mechanism;

Fig. 5 is a section on the line 5—5 of Fig. 4;

Fig. 6 is a detail view of a bearing bracket for the commutator;

Fig. 7 is a detail view of the horn and mounting bracket, and

Fig. 8 is a section on the line 8—8 of Fig. 7.

The construction shown in the drawing comprises a pull switch mechanism 10 adjustably mounted in a canopy 11. This pull switch mechanism is adjustably secured to

the canopy by means of the horn or chain guide 12, through which the pull chain 13 extends.

In order that the pull switch mechanism 10 may be properly supported in the canopy 11, it is made angularly adjustable with respect to the horn 12 secured to the canopy, so that the pull switch mechanism may be tilted to bring it into position to be supported by the canopy 11, as indicated at 53 the points 14 and 15. Thus the pull switch mechanism 10 can be tilted until some part 58 of it comes into contact with some part of the canopy to give it a support in addition to the support furnished it by the clamp- 63 ing action of the horn 12 on the canopy 11.

This angular adjustment between the horn 12 and pull switch mechanism 10 is effected by mounting the horn 12 on a curved bracket 16. As shown in Fig. 8 the horn 70 12 has a threaded shank portion 17 which extends through an opening in the canopy 11 (Fig. 1) and also through the slot 18 in the curved bracket 16, and is threaded into a nut 19. When the parts are in assembled position as shown in Fig. 1, and the shank 17 is screwed tightly into the nut 19, the result is to draw the bracket 16 firmly against the canopy 11, the canopy being clamped between this bracket and the 75 outer portion of the horn or chain guide 12.

In order to prevent the nut 19 from turning when the shank of the horn 12 is screwed into it, the bracket 16, which may be a sheet metal stamping, is provided with 80 integral parallel cheek pieces 20, between which the nut 19 lies. To further assist in positioning the nut 19 and holding it in place, the bracket 16 is provided with a turned up portion 21, which will assist in 85 holding the nut in place when the horn 12 is unscrewed from the nut. The bracket 16 is held in place on the insulating switch base 22 by means of a pair of screws 23 (Figs. 4 and 5) extending through registering openings in the bracket 16 and switch base 22, and threaded into the anchorage brackets 24 respectively.

The switch mechanism per se forms no part of the invention claimed in this ap- 100

application. In a general way it comprises a rotatable commutator or cam wheel 25, mounted in a recess 26 in the insulating base 22, and given a step-by-step movement 5 by means of a pull chain 13. Successive movements of the cam wheel 25 make and break the circuit between the wiring terminals 27 and 28 of the switch.

The cam wheel 25 comprises a conducting cam 29, terminating in a relatively large drop at 30, and a non-conducting cam 31 terminating in a relatively small drop at 32. Cooperating with these cams 29 and 31 are a pair of yielding contact members 33 and 34, the contact 34 being electrically connected with the wiring terminal 27, and the contact 33 being insulated both from the rotatable contact 29 and the contact 34 in the off position of the 10 switch as shown in Fig. 3. The rotatable cam 29 is always electrically connected with the wiring terminal 28 through the inwardly extending conducting arm 35 and the switch shaft or pin 35^a, which is mounted 15 in a hook-like bearing bracket 36 formed as an integral part of the stamping from which the binding plate 37 of the wiring terminal 28 is formed.

With the switch in off position as shown 20 in Fig. 3, if the chain 13 is pulled to move the cam wheel 25 through 180 degrees, this gradually brings the contact 33 into engagement with the contact 34 and when the contact 33 snaps off from the small drop at 25 33 on the conducting cam 29, the circuit is established between the wiring terminals 28 and 27 through the contacts 34, 33 and 29, and the radially extending conductor 35, switch pin 35^a and bearing bracket 36.

When the switch is in "on" position, and the chain 13 is pulled to move it to "off" 30 position, at the latter part of the movement the contact 33 snaps off from the rear end of the conducting cam 29, and because of 35 the relatively great drop, the contact 33 snaps out of engagement with the contact 34 so that the circuit is broken at two points.

An insulating cover 38 (Fig. 5) is provided to cover up the switch mechanism, 30 this cover 38 being secured to the insulating base 22 by means of a pair of screws 39 threaded into the anchorage members 24.

In mounting the switch on the canopy, the switch with the mounting bracket 16 35 is placed in position in the canopy with the bracket 16 adjacent the opening in the canopy, the shank 17 of the horn 12 is inserted through the opening and threaded 40 into the nut 19, and the switch is then slipped in one direction or the other if necessary to bring it into bearing engagement with the canopy as indicated at 14 and 15, so that the switch will be firmly supported. The horn 12 is then screwed 45 up tightly to hold the switch in the posi-

tion in which it has been adjusted. Thus the switch is firmly supported for smooth operation.

While I have shown but one embodiment 70 of my invention, it is obvious that it may be embodied in other forms as covered and defined in the appended claims.

Having thus described my invention, what I claim as new and desire to secure by Letters Patent of the United States is— 75

1. A pull switch mechanism comprising an insulating base, a pull switch mechanism mounted thereon, a pull member, a curved slotted bracket, a tubular guide for the pull member having a shank portion extending 80 into said slot whereby relative adjustment between said curved slotted bracket and tubular guide may be effected, and a nut into which said shank is threaded.

2. The combination with a canopy having 85 an opening therein, of a pull switch mechanism comprising an insulating base, a circuit controlling mechanism mounted thereon, a flexible pull member for operating said circuit controlling mechanism, a curved supporting member secured to said insulating base, and a tubular guiding and attaching member for guiding said pull member and clamping said curved supporting member on said canopy, said curved 90 supporting member being adjustable relatively to said guiding and attaching member, whereby said insulating base may be adjusted in position to be supported by said canopy.

3. A pull switch mechanism comprising an insulating base, a circuit controlling mechanism mounted thereon, a flexible pull member for operating said circuit controlling mechanism, a tubular guide for said pull member, a curved supporting member secured to said insulating base, on which member said tubular guide is mounted, and means for securing said tubular member in various positions along said curved member 105 to effect relative angular adjustment between said tubular guide and said insulating base.

4. The combination with a canopy having 110 an opening therein, of a pull switch mechanism comprising an insulating base, circuit controlling mechanism mounted thereon, a flexible pull member for operating said circuit controlling mechanism and a tubular guiding and attaching member 115 adjacent said opening for guiding said pull member and securing said insulating base on said canopy, said insulating base being angularly adjustable with respect to said tubular member whereby it may be adjusted 120 into position to be supported by said canopy.

5. A pull switch mechanism comprising 125 an insulating base, a circuit-controlling mechanism mounted thereon, a flexible pull 130

member for operating said circuit-controlling mechanism, a support and means for guiding said pull member and clamping said insulating base on said support comprising a tubular screw-threaded member through which said flexible pull member passes, and a member secured to said in-

sulating base and having screw-threaded engagement with said screw-threaded tubular member.

10

In witness whereof, I have hereunto subscribed my name.

REUBEN B. BENJAMIN.
